TELEPHONE REPEATING APPARATUS

Pier Carlo Ricchiardi, Paris, France

Application May 29, 1933, Serial No. 673,545
In Italy June 11, 1932

17 Claims. (CL 179—6)

My invention relates to improvements in telephone repeating apparatus, and more especially to a device whereby it is possible to receive and deliver messages in the absence of a party at the receiving end of a telephone installation.

One of the objects of my invention is to provide an apparatus which functions automatically to raise the receiver hook upon receipt of a signal, and by means of associated electrical and mechanical apparatus, to invite the party calling to leave a message and to deliver a desired message to that party and none other.

Another object of my invention is to provide an apparatus which may be associated with the ordinary dial telephone installation to carry out the above-mentioned objects without necessitating a change in the installation, i. e., it is to supplement and not to replace the installation, thus making it more practicable and desirable.

Another object of my invention is to provide an arrangement which will permanently record incoming messages automatically at the will of the receiving party, regardless of whether or not he is present at the time.

Still another object is to provide an apparatus which may be used not only to permanently record speech from another telephone, but may also be used to provide a permanent record of material dictated to it.

The invention makes use of what is commonly called the Poulsen type of recording or electromagnetic recording of variable electrical currents on a moving wire. This, of course, it merely my preferred form of recording and reproducing of electrical impulses and I may substitute just as easily gramophone discs of optical engraving (i. e., what is commonly known as sound on film recording). The engraving system per se is not the invention, hence my specific showing without modification in conjunction with my invention.

Broadly speaking, the apparatus is so arranged that when an electrical signal is received at the receiver (usually the bell signal), the receiver hook is automatically lifted to place the apparatus in an operative condition. The person calling hears a so-called general message which informs him of the absence of the receiving party. The person calling then dials on a second provided dial his own specific code number, this dialling serving to condition the apparatus to deliver to him the message that has been left for him by the absent party. Strangers calling would have only one chance out of a large number of thousands of dialling the correct code number, hence for all practical purposes the pri-

vate message may not be intercepted. Then when a definite time interval has elapsed, this being determined by the action of a retarded type relay, the apparatus is conditioned to receive and record any message the caller may choose to leave.

The invention may best be understood by reference to the drawings, in which there is shown in Figures 1, 2 and 3, which should be arranged consecutively on the correspondingly lettered lines, a composite diagrammatic view of a preferred embodiment of the present invention, in which embodiment a steel magnetic wire is utilized as recording and reproducing means, the private messages to be delivered being five in number.

In the space enclosed by the dotted lines, there is diagrammatically shown a normal automatic telephonic apparatus. 2—3 are the lead wires of the telephone line, 4 is the telephone receiver including the telephone and the microphone usually detached from hook 5. The current passes in the known direction through the circuit of the telephonic receiver and actuates the bells, thus causing them to vibrate.

Movement of the striker 6 of the bell, grounded at 9, causes the two contacts 7 to touch contacts 8. The circuit including 9, striker 6, contacts 7, 8, conductor 10, relay 11 and positive terminal 12 is thus closed. Relay 11, thus energized, attracts its armature 13 which keeps hook 5 in its lower position. Said hook, pushed by its spring, will swing up and bring into circuit the whole of system 1. This operation avoids the manual unhooking of the telephone receiver at the time of a call. When moving upwardly, hook 5 causes tooth 15 with which it is provided, to strike against small lever 16, which by rotating about 17, forces the arm portion 18 against the resilient contact member 19, which in turn touches contact 20.

Contacts 19—20 will thus be closed, but this closing will only be momentary since the further displacement of tooth 15 will bring it beyond small lever 16 which, pushed by the resilient contact member 19, will come back into its position of rest.

By closing contacts 19—20, a circuit is closed which starting from the grounded side of contact member mass 19 passes through contact 20, conductors 21, 22, 23, 24, winding of relay 25, conductor 26 and direct positive terminal of feed battery 27, the negative terminal of said battery being grounded. Relay 25, thus energized, will attract its armature 28 which will bear against contact 29 thus connecting positive terminal 30

to all of the parts of the apparatus. It has been seen that the closing of contacts 19-20 was momentary. The impulse of current will therefore energize relay 25, but once the current has been cut off said relay will not release its armature 28, but will keep it attracted for a supplementary period of time as above explained, being a retarded type relay.

In the meantime, arm 5 will have reached the end of its course thus applying contact 31 (connected to ground 33) against contact 32. This will close a circuit comprising grounded negative terminal 33, contact 32, wire 34 and motor 35, and a grounded source of potential. Motor 35 thus energized will begin to run.

Thus we see that the apparatus is now on the line, that the positive terminal of the feed battery is now in contact with all the positive terminals of the system (through the action of relay 25), and that motor 35 is running.

Telephone lines 2-3 are now in contact with the arms 38-39 of switch 40 through conductors 36-37. If said arms 38-39 are now brought against contacts 41-42, the apparatus, through conductors 43-44, works as an ordinary automatic telephone, use being made of the telephone microphone system 4. When the owner of the telephone installation has to leave, and only in this case, arms 38-39 are applied against contacts 45-46, the circuit of the line then passing through contact 45, conductor 47, primary 48 of a transformer, conductor 49, secondary 50 of another transformer, conductor 51 and contact 46, which is connected to the telephone line.

35 The four arms 52, 53, 58, 59 of switch 40, if they are applied against contacts 54, 55, 62 and 63, respectively, enable the receipt of telephone conversation through a loud speaker and for transmitting through a table microphone, so as
40 to allow a communication without it being necessary to keep the telephone combined receiver and transmitter in hand. This is the desirable hookup when the person that is called is present.

In the case of the desired party being absent, switch arms 38, 39, 52, 53—58, 59 are applied against contacts 45, 46, 56, 57 and 60—61 respectively. Let it be supposed that a pulsating or alternating current of speech frequency flows through the telephone line. By flowing through the circuit above described, the current flows through the primary of transformer 48. This passage of current will induce in the secondary 48bis, a current which, by energizing the grid of amplifying tube V1, will produce an amplified current flowing through the primary of transformer 64 and through the conductors 22, 23, 24 into the windings of retarded relay 25 (thus energizing it as already explained) and from said windings to the positive terminal of the supply battery. The current from the line thus amplified will induce in secondary 65, a current which, on one side of conductor 66, flows to arm 52, and, on the other side, flows through conductor 67 through the windings of a relay 68, conductor 69, electro-magnet 70, conductor 71 and arm 53. If, as already explained, the person that is called is present, the two arms 52—53 are applied against contacts 54—55; the current from the line (the conversation from the caller) after the amplification above described, will be reproduced by loud speaker 72. If, on the contrary, arms 52, 53 are applied against contacts 56—57, the apparatus will be in position for electro-magnetically recording the words of the caller.

75 Let it be again supposed that the person that

is called is present. In the same way as it has been explained that the telephone conversation was received by means of a loud speaker, the person called may answer by means of the microphone. The two arms 58-59 are then applied against contacts 62-63. The currents set up by microphone 73 are conveyed to the transformer 74, and a current will flow through the following circuit: conductor 75, contact 63, arm 59, conductor 80, the primary winding of transformer 79, conductor 78, arm 58, contact 62, conductor 76 and the secondary of transformer 74. The current flowing through the primary of transformer 79 will produce in the secondary thereof a current that will energize the grid of the amplifying tube. The amplified current will flow from the plate through the primary of transformer 50 through the positive terminal of the supply battery to ground. The amplified current induced in the secondary of transformer 50, flows through the following circuit; arm 38, contact 46, conductor 51, secondary of transformer 50, conductor 49, conductor 47, contact 45 and arm 39, it having been explained that arms 38 and 39 are connected to the line. The current set up by the microphone will thus be amplified and sent directly into the telephonic line. All this, as already stated, takes place when the person that is called is present. In the case of his absence, now considered, the two arms 58-59 will have been brought against contacts 60-61 and the currents set up in the coils by the passage of the magnetized wire between them, will replace those produced by the voice in microphone 73.

The working of the apparatus in the case of the presence of the person that is called has thus been explained. It has been explained that in the case of the absence of this person, the recording apparatus is substituted for loud speaker 72, and the dictating system is substituted for microphone 73. It has also been explained that arms 39-38 of switch 40 will have been applied against contacts 45-46, while arms 52-53 and 58-59 will have been applied against contacts 54-55 and 62-63 respectively. 35 40 45

Let us now see the automatic operations of advising the caller of the absence of the person that is called, and of inviting him to dictate the message that he wants to deliver.

We have already explained the different operations of unhooking the receiver and placing it on the line, and of energizing retarded relay 25 and of starting motor 35. 50

The shaft of motor 35 is rigidly connected with the spindles of spools 85A, 91A, 86A, 86B, 86C, 86D, 86E and spools 85B, 91B, 87A, 87B, 87C, 87D, 87E, through mechanical coupling means that are not illustrated for the sake of simplicity of the drawings. These spools are each rotated through frictional means so that while one of them is being rotated, for instance, the others are stopped by a stop tooth as will be hereinafter explained. However, for the sake of clearness, the drawings do not show the mechanical organs that permit of rewinding the steel wire when the wire has been completely unwound from one spool and is wound around the corresponding spool.

Spool 85B is wound with magnetic steel wire that has not been already engraved, the wire passing between the cores of electro-magnets 88-89 and winding itself on spool 85A. 70

In a similar manner, spools 87A, 87B . . . 87E are wound with steel wire which has been magnetically engraved already, and each spool corre- 75

sponds to a message engraved on its wire, which, passing between the cores of electro-magnets 88-89, will then wind around corresponding spool 86A, 86B . . . 86E. On the contrary spool 91A is wound with a wire on which has been recorded in advance by magnetic engraving, a sentence, which, for instance, notifies for instance the caller of the absence of the person that is called, invites him to transmit this message and 10 to dial the code number or key number for receiving the message dictated by the person that is now being called, in the absence of said person.

This message, which has been electromagnetically engraved on the wire wound around spool 91A, is delivered to anyone that calls this installation, and is wound between spools 91A-91B in spiral fashion so that as soon as the sentence is finished the beginning of the message on the wire is positioned opposite the cores of electro-magnets 20 89-88, account being taken of the inertia necessary for giving the wire a normal speed of translation.

Electro-magnets 89-88 diagrammatically form the so-called "Poulsen" speaking group. As a matter of fact, for practical purposes, the electro-magnets are of a different form and are four or six in number instead of two. Since this "speaking group" is not the object of the invention, it has been shown diagrammatically. Thus one 30 may provide either a "speaking group" for each spool, or one common to all the spools, the magnetic wires being positioned so as to pass the magnet cores side by side.

As has been explained, the energizing of retarded relay 25 takes place at the beginning of the rotation of motor 35. This relay 25 will attract its armature 28, and will thus connect the positive terminal of feed battery 27 to contact 29.

This closes a circuit which includes terminal 40 27, armature 28, conductor 99, conductor 100, the winding of electro-magnet 101, conductors 100, 102 and 103, contact 104, regulating bar 114 and grounded negative terminal 105. The electro-magnet 101 thus energized will attract its armature 107, said armature being rigidly connected to stop teeth 111 which locked the spool. The latter, released by said stop teeth, will be frictionally driven by the shaft of motor 35, and will thus cause the magnetic wire already wound around 50 spool 91A to pass to the other spool.

At the same time as spool 91B is released by teeth 111, armature 107 is joined with contact 108. This closes the circuit which includes negative terminal 105, regulating bar 114, contact 104, 55 conductor 103, armature 107, contact 108, conductors 109, 110, 112, winding of relay 92 and positive terminal 113. Relay 92 is energized and thus attracts armatures 94-93 (which are rigidly connected to each other) and forces them against 60 contacts 97-98 respectively.

The wires of spool 91A, magnetized in advance by the well known "Poulsen" effect, by passing between the cores of electro-magnets 88-89, will produce a variation of the magnetic field generated by the current supplied by battery 135, said current flowing in the windings of electro-magnets 88-89. Each variation of the field will induce an alternating voltage in the windings surrounding electromagnets 88 and 89 according to well known electrical principles and as a consequence, at a given time, a current will flow through conductors 116 and 117, armature 93, contact 98, conductor 119, battery 135, contact 61, arm 59, conductor 80, primary of transformer 79, conductor 75 tor 78, arm 58, contact 60, conductor 120, contact

97, armature 94, conductors 121 and 122, and the windings of electro-magnets 88-89.

The currents thus induced by the passage of the wires containing the electro-magnetically recorded message dictated in advance, will flow through the primary of transformer 79, and induce in its secondary currents that will be amplified by tube V2, and conveyed to the telephone line through the circuits previously described.

If, while this message is being delivered by the 10 apparatus that has been called, the caller happens to speak, this will have no effect whatever on electro-magnets 88-89 of the "speaking group" because of the opening of the contacts of relay 92 and of the circuit of amplifying tubes 15 V1-V2.

Therefore, the apparatus is now working only as a transmitter, and the caller hears in his receiver the notification of the absence of the person he had called, and, for instance, an invitation 20 to transmit a message that will be recorded.

Once this communication is ended, the apparatus is automatically brought into its receiving position as will be hereinafter explained.

A regulating bar 114A . . . 114F slides on each 25 spool respectively. It represents diagrammatically any mechanical device adapted to open contacts 104 and 125 when the desired portion of the wire that was wound around spool 91A has been transferred to spool 91B. This portion of wire 30 corresponds to the length of the sentence to be transmitted, and the adjustment of this portion is effected by suitable cooperation with bar 114.

The wires of spool 91A differ from those wound around spools 87A . . . 87E, since the message, 35 once delivered, is to be wound, not on spool 91B, but again on spool 91A. To this effect, it has been explained that it had to be wound so as to form an endless spiral.

When the whole message has been delivered, 40 the contact of 104 with bar 114 is cut off so that electro-magnet 111 is no longer connected to the negative terminal 115, and consequently releases stop tooth 111. This stops spools 91A, 91B and opens contacts 94-97 and 93-98 of relay 92. Bar 45 114 is moved away from contact 104 and rests on contact 125. This will close the following circuit: negative terminal 105, bar 114, contact 125, conductors 106, 126, relay 127, conductor 128, contact 129, axis of distributor 133, contact 131 and positive terminal 132.

The contact of distributor 130 is so arranged that, when applied against contact 131, it is also applied on contact 129 located opposite it.

Electro-magnet 127 will therefore be energized, 55 and will attract stop tooth 130.

Motor 35 is still revolving, and spool 85A, released by stop tooth 133 and frictionally driven by the shaft of said motor, will turn and thus wind on its periphery, the wire that was wound around 60 corresponding spool 85B.

As it has been stated, this wire has not yet been magnetized and by passing between the cores of electro-magnets 88-89 when the current from the telephonic line flows through said electro-magnets, the words or message dictated by the caller is recorded.

I have first explained the working of the apparatus as a transmitter when it was called from another telephone installation. Its action as a 70 recording receiver is as follows. By breaking the contact between 104 and bar 114A, not only has relay 92 been stopped, but also relay 92 has been deenergized since it has been cut off from grounded negative terminal 105. There- 75

fore no current will flow through relay 92, and the armatures 94-93 which, until now, were applied against contacts 97-98, are moved away from said contacts thus opening the dictating 5 circuits.

The two armatures 94-93 thus released will make contact with contacts 95-96 respectively, thus closing the receiving and recording circuit which comprises electro-magnet 88 (which now 10 acts for recording), conductor 121, armature 94, contact 95, conductors 118 and 136, contact 56, arm 52, conductor 66, secondary of transformer 65, conductor 67, winding of relay 68, conductor 69, relay 70, conductor 71, arm 53, contact 57, conductor 137, contact 96, armature 93, conductors 117 and 116, winding electro-magnet 89, conductor 123 and electro-magnet 88.

It has explained previously through which circuit the telephone current of the line is conveyed 20 to the amplifying tube V1 when the apparatus works, as in the present case, as a recorder and receiver, and through which circuit the current is amplified by tube V2 when the apparatus 25 works as a dictating transmitter.

25 The current from the line (that is to say, the answer of the caller to the message he has just received and which had been dictated to the apparatus by the person that was called) will be amplified by tube V1, and the secondary of transformer 30 65, and, flowing through the circuit above described, will be fed to electro-magnets 88-89.

The current that flows through said electro-magnets and therefore the flux between the cores of said electro-magnets, will vary proportionally 35 to the variations of current in the telephonic line. The steel wire that passes between the cores will be magnetized in a varying manner at each point, proportional to the current flowing in the winding of electro-magnets 88-89.

40 The words or the message dictated by the caller will therefore be magnetically recorded on the steel wire according to the "Poulsen" system.

When the answer of the caller is finished, no current will flow from the telephone line, and 45 also in the plate circuit of tubes V1-V2 (which are normally adjusted in such manner that the normal plate current is insufficient to actuate retarded relay 25). The current necessary for keeping retarded relay 25 energized will thus fail, 50 and after the energizing current has been stopped for a certain time, relay 25 will release its armature 28.

It has been stated previously that the object 55 of the retarded relay is to allow a certain time interval to elapse between the call and the beginning of the conversation at the calling installation, and also short stops in the dictation, without immediately cutting off the connection.

After this period of time has elapsed, relay 60 25 will release its armature 28, as when the communication is terminated.

It should be noted that all the positive terminals shown in the drawings do not relate directly 65 to the positive terminal of the feed battery, but to the positive terminal 30, which is connected through conductor 99 to contact 29 which in the operative working position of retarded relay 95 is in contact with armature 28 70 directly connected to the positive terminal of the feed battery.

When retarded relay 25 is deenergized, armature 28 moves away from contact 29, thus breaking 75 the motor voltage supply and restoring the other circuits to their normal positions.

The motor, the relays, and all the other apparatus therefore assume their normal positions.

In order to disconnect the apparatus from the telephone line, it is now necessary to automatically perform the operation, normally carried out by hand, of lowering the hook that supports the receiver, and to keep it lowered. This is done in the following manner: As the armature 28 of retarded relay 25 is no longer attracted by the relay, not only does it move away from contact 99, thus restoring the apparatus to its normal position, but it is applied against contact 140 thus closing a circuit including positive terminal 27, armature 28, contact 140, conductor 141, relay 142, conductor 143, contact 144, armature 145 and grounded negative terminal 146.

The relay 144 that is thus fed will attract its armature 145. The latter is in turn rigidly connected with hook 5 through bar 147. By lowering armature 145, hook 5 will be lowered, and by 20 rubbing against armature 13 of relay 11, it will be locked under said armature, therefore remaining in this lower position. As armature 145 is rigidly connected to hook 5, it will also remain in its lower position, and accordingly contacts 144-145 through which pass the current of relay 142, will be opened.

This prevents current passing in a continuous manner through relay 142 when the apparatus is unused.

I will now explain the working of the apparatus with respect to its characteristic of transmitting private messages.

I have already stated, the possibility of transmitting five private messages, but obviously an 35 unlimited number of said messages can be transmitted. The five particular messages are recorded on wires wound around spools 87A, 87B . . . 87E . . . When one of them is transmitted to a caller, it is wound on the respective 40 spool 86A, 86B . . . 86E . . .

The means utilized for these transmissions are identical to those already described with reference to spool 91A, the only difference being in the starting, since the spools now considered are 45 started not by the call signal as explained for the common or general messages (spool 91A), but by a special signal transmitted by the calling telephone installation. Therefore, once the common or general message notifying the absence of the person that is called has been transmitted, the problem for the caller is to operate among spools 87A . . . 87E, the one that will transmit the message left for him by the person that he calls, and who is absent.

Each apparatus is provided with a dial C2 exactly similar (as for its working principle) to that of the automatic telephone apparatus C1. The presence of this second dial C2 is due to the fact that it is desired to avoid any modification 60 of the equipment that comprises a telephone installation, so as to permit of being wholly independent of said installation. It is obvious that, if this consideration is considered unimportant, it is possible to use the same telephone dial by utilizing a suitable switch without changing the principle of this invention.

This dial C2 which is the same as those used 70 for automatic telephones, has on its outer periphery a number disc 212 with corresponding holes for introducing the finger therein, and causing it to rotate it as far as a stopping tooth (not shown in the drawings) when it is desired to close contacts 216-217, a certain number of times.

In ordinary dials, the displacement of part 213 is obtained through a toothed wheel 210 having ten teeth corresponding to the figures of the disc, and the toothed wheel is caused to rotate, 5 not directly when numbered disc 212 is rotated by hand, but by means of a spring which in turn will rotate the toothed wheel by a number of teeth equal to the number corresponding to the hole in which the finger was inserted. As for an ordinary telephone dial, roller 211 carried by bar 213 will move over the outline of the toothed wheel, and therefore is number 3 for instance is dialed, three teeth will pass on roller 211 thus imparting three pulsations to bar 213, thus closing contacts 216-217 thrice. As above stated, this closing of the contacts takes place through the intermediary of a spring, and during the backward rotation of numbered wheel 212. During the tensioning of said spring a small bolt 200 10 is brought against crank lever 202 which is pushed downwardly by pivoting about a point 204, and causes arm 203 to apply contacts 205-206 against each other. At the same time, small bolt 200 will move past said bell crank 15 lever 202.

During the backward rotation of the wheel, bolt 200 will merely raise lever 202 without pushing it against contact 206.

It can therefore be seen that at the beginning 30 of the dialing of a key number, or to be very accurate, when each figure that goes to form said number is dialed, contacts 205-206 will be applied against each other, closing the following circuit: negative terminal 208, conductor 207, contacts 206-205, conductor 218, relay 220, conductors 219-223 and positive terminal 221. Relay 220 is energized by a pulsation of current. This relay will attract its armature 227 which, 35 being immediately released, will break into oscillation in the manner of a tuning fork at a frequency that is well determined and defined by the thickness, length, outline and grade of the steel of which it is made.

As this blade is so chosen as to have its frequency of oscillation in the range of audio frequencies, it will oscillate in the magnetic field produced by coil 301 within which said blade is located. This magnetic field is produced by the 40 constant current flowing from positive terminal 307 into the primary of transformer 306, conductors 305-228, coil 301, conductor 303 and negative terminal 304.

This permanent magnetic field will therefore vary in accordance with the vibrations of armature 227, that is to say at a constant frequency F1, which is the natural frequency of oscillation of plate 227.

But these variations of the permanent magnetic field produce variations in voltage at the 45 terminals of coil 301, and therefore at the terminals of the primary of transformer 306, through conductor 305. It is therefore clear that, for each displacement of small bolt 200 of numbered wheel C2, that is to say whenever a figure 50 of the key number is dialed, there will be impulses of alternating current in the primary of transformer 306, the frequency of this current being determined by the natural frequency of oscillation of armature 227.

Therefore in order to dial a key-number, for instance number 54322, numbered wheel 212 will be rotated so that number 5 is brought against the stop tooth, thus causing the armature 227 to vibrate at a frequency F1, and this will cause 55 a current of a frequency equal to F1 to flow

through the primary 306 of the transformer. By thus bringing number 5 of wheel 212 into contact with the stop tooth, the spring cooperating with said wheel 212 will have been tensioned, and as soon as said wheel is released by the finger, it will begin to rotate backwards, toothed wheel 210 moving by five teeth. This means that lever 213 will be displaced five times, and will therefore close contacts 216-217 five times at regular intervals.

5

The closing of these contacts will close the following circuit: negative terminal 208, conductor 209, contacts 216-217, contact 225, relay 222, conductor 223 and positive terminal 221. As already explained for electro-magnet 220, 15 electro-magnet 222 will attract its armature 226, which will in turn oscillate at its natural frequency.

10

This frequency current, which is quite different from the current of frequency F1, is 20 produced by the oscillations of armature 227, will be called F2, and it will flow through the primary of transformer 306.

Furthermore, as number 5 has been dialed, contacts 216-217 have been closed five times, 25 and therefore electro-magnet 222 has been energized five times. Consequently five pulsations of current at a frequency F2 have been produced in the primary of transformer 306.

When number 4 is then dialed (the key number 30 cited by way of example being 54322), there is produced in transformer 306, first a pulsation of current at a frequency F1, and then four pulsations at a frequency F2; when number 3 is dialed there is a pulsation at a frequency F1 35 and then three pulsations at a frequency F2. When each of the numbers 2 is dialed, there is first a pulsation at a frequency F1 and then two pulsations at a frequency F2.

These pulsations of current at low frequencies, 40 by flowing through the primary 306 of the transformer, will induce currents of equal frequency in the secondary 308 of this transformer.

From said secondary, these pulsations of current will flow to amplifying tube V3. Amplified 45 pulsations of current will thus be set up in the primary 310 of a transformer, thus inducing pulsations of current in the secondary 312 of this transformer. These pulsations of current are conveyed to the telephone line through conductors 313-314, contacts 39-38, and conductors 36-37.

I will now explain what takes place at the telephone installation of the person that is 50 called. As above described, when the call signal 55 is received, all the operations of branching the telephone installation to the telephone line take place. The apparatus transmits to the caller the general message or invitation to dial the key-number.

When this general message has been transmitted, and the steel wire or ribbon of spool 91A has been entirely unwound, the apparatus, which, as already explained, acted as a transmitting and 60 dictating system, now becomes a receiving and recording system, and now begins to unwind the recording spool 85B. It has been supposed, by way of example, that the key-number consisted of five figures (54322). Each apparatus is provided with five (if the number of key-numbers 65 and of messages available at this installation is five, six if there are six key-numbers and six messages available at this installation, etc.) pre-selectors of the type usually employed for automatic telephone installations. Each preselector 70

75

consists of five elements (447A, 447B, 447C, 447D, 447E) for example. Each element carries, at its periphery, ten contacts (from zero to nine) on which can frictionally move one brush for each element (500A, 500B, 500C, 500D, 500E) for example, for the sake of clearness of the drawings, have not been indicated by a number in the successive preselectors. These brushes are rigidly carried by spindles 460, 461, 462, 463, 464. Each spindle is controlled by a relay (144A, 144B, 144C, 144D, 144E) which, for each pulsation of current that passes through it, will attract its respective armatures 145A, 145B, 145C, 145D, 145E. Each of these armatures engages by its hooked end between teeth carried by the spindle of the preselector and its displacement will cause the corresponding brush 500A . . . 500E to rotate through an angle corresponding to one tooth, one of the contacts disposed on the periphery of each element of the preselector being correspondingly rotated.

Each "message" will be characterized by the starting of one element of each preselector. For the first message, there will first be brought into action the element 447A of the first preselector, the element 448A of the second preselector, the element 449A of the third selector, the element 450A of the fourth selector, and the element 451A of the fifth selector.

For the second "message", elements 447B, 448B, 449B, 450B, 451B, will be caused to act.

For the third "message", elements 447C . . . 451C will be caused to act. For the fourth "message", elements 447D . . . 451D, and for the fifth "message" elements 447E . . . 451E, will be caused to act.

By way of example, I will now explain the operation of the apparatus corresponding to the first message. The key-number will be determined by the position of plugs 452A, 453A, 454A, 455A, 456A. These plugs are movable, and each of them can be fixed on one of the ten contacts disposed along the periphery of each element and of each preselector. Plug 452A will be fixed on one of the ten contacts of element 447A, plug 453A on one of the ten contacts of element 448A, etc. Each of these plugs is connected to a brush rubbing against a ring on which is fixed the rotating brush, electrically insulated from the spindle by which it is driven. Thus, plug 452A is connected to sliding contact 501A of the first element of the second preselector; plug 453A is connected to the sliding contact 502A of the first element of the third preselector; plug 454A is connected to the sliding contact 503A of the first element of the fourth preselector; plug 455A is connected to contact 504A; and plug 456A is connected to conductor 520A.

The key-number is defined by the position of plugs 452A . . . 452E, 453A . . . 453E, 454A . . . 454E, etc., on the contacts of the respective elements of the preselector.

I will now explain the operation of the apparatus for a given message.

It has been supposed that the key-number taken by way of example was 54322.

At the telephone installation that is called, plug 452A has been placed in advance on contact number 5 of element 447A; plug 453A has been fixed on contact number 4 of element 448A; plug 454A has been fixed on contact number 3 of element 449A; plug 455A has been fixed on contact number 2 of element 450A; and plug 456A has been fixed on contact number 2 of element 451A. All the rotating brushes are in their position of rest

on the zeros. There will now be explained how the message characterized by key-number 54322 is selected and transmitted. It has been seen that, at the telephone installation of the caller, after having been advised of the absence of the person that is called, the caller, knowing that there is a message for him, has dialed key-number 54322 by means of device C2. This has caused the following pulsations to be emitted into the telephone line: a pulsation at frequency F1 and five pulsations at frequency F2, a pulsation at frequency F1 and four pulsations at frequency F2, a pulsation at frequency F1 and three pulsations at frequency F2, a pulsation at frequency F1 and two pulsations at frequency F2, a pulsation at frequency F1, and two pulsations at frequency F2. The first pulsation of current at frequency F1 coming from the telephone line will flow, through the conductors mentioned in the preceding description, to contact arms 38—39. This current will flow through contact 46, conductor 47, primary 48 of transformer 48—48bis, conductor 49, secondary 50 of another transformer, conductor 51, brush 38, and from there to the telephone line.

These pulsations of current at frequency F1 will be amplified by tube V1, and will then flow through the primary of transformer 65. This will induce corresponding pulsations of current through the secondary of transformer 65, conductor 67, winding of electro-magnet 68, conductor 69, electro-magnet 70, conductor 71, and recording electro-magnets 88—89.

Electro-magnets 68 and 70 will therefore be subjected to a pulsation of current at a frequency F1.

These electro-magnets will attract and release their own vibrating armatures 400 and 401 respectively, at a frequency equal to F1. But one of these blades namely blade 401, is such that its natural frequency of oscillation is exactly equal to that of blade 227 (which has produced frequency F1). Blade 401 will therefore immediately resonate, and this will result in an amplitude of oscillation such that it comes into contact with 405.

On the contrary, blade 400 (the frequency of which is equal to F2) will not resonate and therefore its amplitude of oscillation will not be sufficient for bringing it into contact with 402.

Vibrating blade 401 contacting with 405 will close the following circuit: negative terminal 403, vibrating blade 401, contact 405, conductor 406, electro-magnet 407 and positive terminal 408. The electro-magnet 407, thus energized will attract its armature 410. This armature is engaged by its hooked end 143 in the teeth of a toothed wheel 411 so that its attraction by electro-magnet 407 will cause said toothed wheel 411 to rotate through an angle corresponding to one tooth.

The effect of this rotation will be that brush 130 will leave contacts 129—131 and will be brought upon contact 142A. This will open the circuit through which electro-magnet 127 is energized so that said electro-magnet will release its armature 133, which will engage spool 85A, thus stopping its movement, and causing it to rub on the friction element above mentioned. In this way, the recording on the wire of spool 58A will be interrupted.

It has been seen that after a first pulsation, brush 130 is brought upon contact 142A.

It has also been seen that the transmission of a pulsation at a frequency F1 from the telephone installation of the caller will be followed by five

successive impulses at a frequency F2, when the number dialed is 5.

These pulsations, flowing through the circuits previously described for the accommodation of frequency F1, will also energize electro-magnets 68-70. Blade 400 will be attracted by the electro-magnet 68 due to the effect of the pulsation of current at frequency F2 through the windings of the magnet.

Every time a current pulsation of frequency F2 is received, blade 400, under the effect of the phenomenon of resonance, will be brought into contact with 402, whereas 401, which is not tuned to resonance, cannot be brought into contact with 405. When a pulsation of current of frequency F2 is received, blade 400 comes into contact with 402 and closes the following circuit: negative terminal 403, blade 400, conductor 402, rotating brush 404, brush 130 (now applied against contact 142A) contact 142A, conductor 600A, electro-magnet 144A and a positive terminal. In the specific case chosen as an example, as five pulsations of current at frequency F2 will be received, the contact 400-402 will be closed five successive times.

Relay 144A will thus be energized five times, and it will attract its armature 145A five times.

Armature 145A will therefore cause spindle 460 of the first preselector to rotate through an angle corresponding to five teeth, thus bringing brush 500A with which it is rigidly connected, onto contact No. 5 on which has been placed plug 452A.

As above explained, the calling telephone installation will then transmit a pulsation at frequency F1, and four pulsations at frequency F2 successively.

When the pulsation of frequency F1 flows through magnets 68-70, blade 401 will close on contact 405, thus transmitting a pulsation of current to relay 407.

As it has already been explained, said relay will then attract its armature which, through its hooked end 143, will displace brush 130 and thus bring it on to contact 142B. The four pulsations of current at frequency F2 are then received, and close four times contacts 400-402.

Electro-magnet 144B will thus receive four pulsations of current through the circuit already described and the brush of element 448A will accordingly be brought on to contact No. 4 on which is fixed plug 453A.

A third pulsation of current at frequency F1 will now be received. The brush 130 of the distributor will be brought onto contact 142C. Three pulsations of current at frequency F2 will then be received, and by actuating electro-magnet 144C, they will bring the brush of element 449A of the third preselector onto contact No. 3 on which is fixed plug 454A.

A fourth pulsation of current at frequency F1 will now be received, and after it two pulsations of current at frequency F2 will also be received. The pulsation of current at frequency F1 will cause brush 130 of the distributor to move forward one tooth thus coming onto contact 142D. The two pulsations of current at frequency F2 will cause, through electro-magnet 144D, the brush of the first element 450A of the fourth preselector to come onto contact No. 2 on which is fixed plug 455A.

Finally, a pulsation of current at frequency F1 and two pulsations of current at frequency F2 will be received. The pulsation of current at frequency F2 will cause brush 130 of the distributor to move forward one tooth and to come onto

contact 142E. The two pulsations of current at frequency F2 by means of relay 144E will cause the brush of the first element 541A of the fifth preselector to wipe against contact No. 2 to which is fixed plug 456A.

In this way, it will be seen that when the calling telephone installation transmits the key-number, the brush of element 447 of the first preselector is brought onto contact No. 5, the brush of element 448A of the second preselector is brought onto contact No. 4, the brush of element 449A of the third preselector is brought onto contact No. 3, the brush of element 450A of the fourth preselector is brought onto contact No. 2, and finally, the brush of element 451A of the fifth preselector is brought onto contact No. 2.

It has been explained in a preceding description that the person at the telephone installation that is called has placed plugs 452A, 453A, 454A, 455A, 456A on contacts Nos. 5, 4, 3, 2, 2 of the first element of each preselector respectively. When the brush of the last element wipes against contact No. 2, the following circuit is closed: positive terminal 446A, brush 510A, contact No. 5 (onto which the brush has been brought) plug 452A (fixed before hand on contact No. 5), brush 501A, rotating brush of element 448A, contact No. 4 (onto which the brush has been brought), plug 453A (fixed before hand on contact No. 4) sliding brushes 502A, rotating brush of element 449A, contact No. 3 (on to which the brush has been brought) plug 454A (fixed before hand on contact No. 3) sliding brush 503A, rotating brush of element 450A, contact No. 2, conductor 455A, sliding brush 504A, rotating brush of element 451A, contact No. 2, plug 456A (fixed beforehand on contact No. 2) conductor 520, relay 610A, conductors 612A-613A, contact 614A, control bar 114B and negative terminal 615A.

Electro-magnet 610A thus energized, will attract its armature 620A which is integral with stop tooth 618A of spool 86A. The latter, released by its stop tooth and driven through frictional contact with the shaft of motor 35, will begin to wind the wire containing the magnetically recorded message wound about the corresponding spool 87A, thus transmitting the message intended for the calling telephone installation, this message being dictated in the same way as above described with reference to spool 91A.

It is therefore obvious that a mistake in a single figure, in the dialing of the key-number, will cut the circuit above described so that the transmission of the message will not be possible.

It is therefore necessary to know all of the figures (five in this case) that form the key number in order to be able to obtain the transmission of the message from the telephone installation that is called.

However, before the energizing of relay 610A, the apparatus was acting as a receiving and recording device. It is therefore necessary to cause it to act as a repeating and transmitting device.

Consequently, at the same time as the stop tooth 618A of spool 86A is released, the armature 620A is attracted so as to come into contact with 621A. This closes the following circuit: negative terminal 615A, contact 614A, conductor 613, armature 620A, contact 621A, conductors 611, 110, 112, relay 92 and positive terminal 113. Relay 92 will therefore attract its armatures 93-94 into contact with 97 and 98 respectively, thus bringing the apparatus into transmitting position.

When a message has been entirely delivered, control bar 114B is raised as previously explained. This will cut off the negative terminal 615A from relay 610A so that the armature 620A and consequently stop tooth 618A will be released, thus stopping the rotation of spool 86A.

But the armature 620A, by being released, ceases to be in contact with 621A, and thus cuts off the current flowing to relay 92. The armatures 93—94 of this relay are thus released, and condition the apparatus so that it acts as a receiving and recording system.

When tooth 618A is hooked into spool 86A, this tooth, rigidly connected to armature 620A of relay 610A, comes into contact with 623A.

Stop tooth 618A, which is permanently connected to the positive terminal at 622A now connects this contact 623A to said positive terminal.

When control bar 114B is moved away from contact 614A, it comes into contact with 616A and thus closes the following circuit: negative terminal 615A, control bar 114B, contact 616A, conductors 617A—630, 126, relay 127, conductors 128, 626, 625A, contact 623A, stop tooth 618A and positive terminal 622A.

Relay 127 will thus attract its armature (stop tooth) 133 thereby releasing the recording spool 85A which winds the magnetically recorded wire after it has received the answer from the calling telephone installation.

For the sake of clearness of the drawings, I have omitted the contacts corresponding to 623A of stop tooth 618A for the other electro-magnets 610B, 610C, 610D, 610E.

It is obvious that the circuit for these electro-magnets will be substantially the same as the circuits described for electro-magnet 610A.

For the same reason I have omitted the device that brings the distributor and the pre-selectors back to their zero position when the message has been transmitted.

When the answer from the calling telephone installation has been duly recorded by the apparatus at the receiving telephone installation, all the units of the apparatus resume their normal position of rest through the operations above described.

If it is desired to utilize the apparatus for dictating purposes, it will suffice to bring arms 39—38 on to contacts 41—42 thus inserting the normal microphone-telephone system (4) of an ordinary apparatus, and connecting the microphone to contacts 45—46 by bringing arms 52—53 on to contacts 56—57. Motor 35 is then started by depressing contact 701 against contact 702, and contact 704 will be applied against contact 705 (of spool 85A) in order that the apparatus may electro-magnetically record the words that are uttered.

In order to utilize the apparatus as a dictaphone, it will suffice to energize electro-magnet 92 without moving the contacts above described, by bringing contact 708 (grounded at 707) against contact 709, to connect loud speaker 72 to contacts 54—55 (with which microphone 73 was previously connected) in order that the apparatus may repeat through the loud speaker the words dictated and recorded by means of the electro-magnetic system. The same operation will be performed when it is desired to hear a telephone message recorded by the apparatus during the absence of the person that was called.

My invention is described with particularity in the appended claims.

What I claim is:

1. The combination with a telephone installation having a signal box and a normally depressed receiver hook, of means associated with the receiver hook for automatically lifting the latter on the signal being received, an electric motor, means associated with the receiver hook for starting the motor on the hook being lifted, a telephone electrically connected to the telephone circuit, a plurality of record carriers operatively associated with said telephone for transmitting and receiving messages over the telephone circuit, means for operatively joining one of said record carriers with the motor on the receiver hook being lifted for the transmission of a general message, selecting means operable by the caller over the telephone circuit for operatively joining another record carrier with the motor for the transmission of a special message, means for operatively joining a third record carrier to the motor for recording a message transmitted by the caller, means controlled by the speech current for maintaining the device operative, and means for restoring the receiver hook to depressed position after the speech current ceases.

2. The device claimed in claim 1 in combination with a loud speaker, a microphone, and a switch for connecting said loud speaker and microphone to the telephone circuit instead of the telephone.

3. The device claimed in claim 1 in combination with a microphone, and a switch for connecting said microphone to the telephone.

4. A device as claimed in claim 1 wherein the connection between the bell box and receiver hook comprises an electric circuit including the bell clapper, contacts in said circuit through which the latter is closed when the clapper is operated, a catch holding the receiver hook normally depressed, and a magnet in said latter circuit for operating the catch and releasing the receiver hook.

5. A device as claimed in claim 1 wherein the means for maintaining the device operative comprises an electric source, a retarded relay, means operated by the lifted receiver hook for initially energizing said relay through the source, means controlled by said relay for maintaining all the electric parts of the device connected to the positive pole of the source, and means for passing the speech currents through the relay.

6. A device as claimed in claim 1 wherein the means for maintaining the device operative comprises an electric source, a retarded relay means operated by the lifted receiver hook for initially energizing said relay through the source, means controlled by said relay for maintaining all the circuits of the device connected to the positive pole of the electric source, means for passing the speech current through said relay and means for amplifying said speech currents.

7. The device claimed in claim 1 in combination with a switch for connecting the device to the telephone circuit instead of the ordinary telephone receiver.

8. The combination with a telephone installation having a signalling circuit and a normally depressed receiver hook, of means associated with the signalling circuit and the receiver hook for automatically lifting the latter on the signal being operated, an electric motor, means associated with the receiver hook for starting the motor on the hook being lifted, an electro-magnetic speaking head connected to the telephone circuit, a plurality of record carriers operatively

associated with said speaking head for transmitting and recording messages over the telephone circuit, a plurality of spools holding said carriers and adapted to be frictionally coupled to the motor for rotation thereby, arresting means maintaining the spools and record carriers normally inoperative, a retarded relay, means operated by the lifted receiver hook for initially energizing said relay, means operated by said relay for releasing the spools of one record carrier for the transmission of a general message, selecting means operable by the caller over the telephone circuit for releasing the spools of a second carrier for the transmission of a special message, means controlled by the receiving spools for re-arresting the spools after the transmission of the messages, means operated by the re-arresting means of the last set of spools for releasing the spools of a third record carrier for recording a message transmitted by the caller, means controlled by the relay for maintaining the different circuits operative, means for maintaining the relay energized by the speech current, and means associated with the relay for restoring the receiver hook to depressed position when the relay is de-energized.

9. A device as claimed in claim 8 wherein the means for arresting the spools comprises pivoted catches and wherein the means for releasing the spools comprises electro-magnets adapted to operate said catches.

10. The device claimed in claim 8 in combination with a switch for changing over from reception to transmission and vice versa, an electro-magnet for operating said switch, and means associated with the spool arresting and releasing means for energizing and de-energizing said electro-magnet.

11. A device as claimed in claim 8 wherein the receiving and re-arresting means controlled by the receiving spools comprises in each case a switch lever bearing against and operated by the record carrier.

12. A device as claimed in claim 8 wherein the selecting means comprises a dialling disc, means for producing electric impulses by the rotation of said disc, a series of rotatable switch elements, and means operated by the electric impulses for setting said switch elements.

13. A device as claimed in claim 8 wherein the selecting means comprises a dialling disc, means for producing electric impulses by the rotation of said disc, a series of rotatable switch elements, means operated by the electric impulses for rotating said switch elements, and contacts co-operating with said switch elements and adapted to be electrically connected in dif-

ferent manners for determining the selection of a message.

14. A device as claimed in claim 8 wherein the selecting means comprises a selecting circuit, a dialling disc in said circuit, means operable by the disc for producing electric impulses in said circuit at two different frequencies, means operable by the impulses of one frequency for selecting a set of switch elements, means operable by the other frequency for rotating said set of switch elements, and contacts co-operating with said switch elements and adapted to be interconnected in different manners for determining the selection of a message.

15. A device as claimed in claim 8 wherein the selecting means comprises a selecting circuit, a dialing disc in said circuit, means operable by the disc for producing electric impulses in said circuit at two different frequencies, a preselector in said circuit, a series of rotatable switch elements, means operable by the impulses of one frequency for connecting the pre-selector electrically with different sets of switch elements, means operable by the other frequency for rotating the switch elements, and contacts co-operating with said switch elements and adapted to be interconnected in different manners for determining the selection of the message.

16. A device as claimed in claim 8 wherein the selecting means comprises a selecting circuit, a dialling disc in said circuit, means operable by the disc for producing electric impulses in said circuit at two different frequencies, a pre-selector in said circuit, groups of coaxial rotary switch elements, means operable by the impulses of one frequency for connecting the pre-selector electrically and in succession with the different groups of switch elements, means operable by the other frequency for rotating the switch elements of each group through a given number of steps, and contacts co-operating with said switch elements and adapted to be interconnected in different manners for determining the selection of a message.

17. A device as claimed in claim 8 wherein the means for restoring the receiver hook to depressed position comprises a magnet, an armature for said magnet connected mechanically to the hook a circuit for said magnet including the armature and a contact against which the armature bears when the hook is in raised position, and means released by the retarded relay for passing current through said magnet circuit when the relay becomes de-energized.

PIER CARLO RICCHIARDI.
